UNITED STATES PATENT OFFICE

2,454,601

NUTCRACKER WITH AN ADJUSTABLE
SLIDING JAW

William M. Gallagher, Oklahoma City, Okla.

Application April 12, 1945, Serial No. 587,871

2 Claims. (Cl. 146—16)

1

This invention relates to nut crackers.

An object of the invention is the provision of a nut cracker in which a pair of substantially rigid arms are connected together at a pair of the adjacent ends by a spring member so that the free ends of the arms will tend to be spread apart while permitting the free ends to be moved towards each other when cracking a nut, a lug projecting from each arm intermediate the ends thereof with the free ends of the lugs adapted to contact each other when the free ends of the arms are moved towards each other for limiting the inward movement of said arms and therefore controlling the crushing pressure of a pair of jaws on the arms and adjacent the lugs for preventing the meats of the nuts from becoming broken.

Another object of the invention is the provision of a nut cracker in which a pair of arms are connected together at one end by a spring member, thereby leaving the other ends of the arms free to be manipulated, means being employed for limiting the inward movement of the free ends of the arms for controlling the breaking pressure on the nuts, one of the arms having a nut receiving jaw, the other arm having a wedge-shaped jaw adjustably mounted thereon for taking care of nuts of various diameters.

A further object of the invention is the provision of a nut cracker in which a pair of arms are connected together by a spring so the opposite ends will be free for movement towards or away from each other, said arms intermediate the ends being provided with the lugs being in alignment so that their free ends will contact and limit the inward movement of the arms, one of the arms adjacent the lug thereon being provided with the fixed jaw to receive a portion of a nut, one face of the lug on the last mentioned arm being curved towards the jaw, the lug on the other arm being provided with a slot, a wedge-shaped jaw slidable on the last mentioned arm and received by the slot, said wedge-shaped jaw being movable towards or away from the spring member to accommodate nuts of various diameters, between the movable jaw and the fixed jaw.

This invention will be best understood from a consideration of the following detailed description, in view of the accompanying drawings forming a part of the specification; nevertheless, it is to be understood that the invention is not confined to the disclosure, being susceptible of such changes and modifications as define no material departure from the salient features of the invention as expressed in the appended claims.

2

In the drawings:

Fig. 1 is a side view in elevation of a nut cracker constructed according to the principles of my invention.

5 Fig. 2 is a front end view in elevation of the nut cracker.

Fig. 3 is a view in perspective of a movable jaw.

And Fig. 4 is an enlarged vertical section taken along the line 4—4 of Fig. 1.

10 Referring more particularly to the drawings, 10 generally designates a spring member which has a thickened portion 11 and a pair of semi-circular members 12.

An arm 13 is connected to the member 10 by 15 the semi-circular spring portion 12. An arm 14 is connected to the member 10 by the semi-circular spring portion 12. The semi-circular members 12 are formed of spring steel in order to maintain the free ends of arms 13 and 14 outwardly from each other so that when the arms are moved towards each other manually and then released, the free ends of the arms will spring apart.

25 The arm 13 is provided with a lug 15 projecting towards a lug 16 on the arm 14. The free ends of these lugs are spaced from each other but are adapted to come into contact with each other when the arms 13 and 14 are moved together. These lugs are of sufficient length to 30 permit the cracking of the shell of the nut before the lugs contact in order to prevent the crushing of the meat of the nuts.

The arm 13 is provided with a curved seat or 35 jaw 20 and it will be noted from Fig. 1 that one side face of the lug 15 is curved; and this curved face merges into the curved seat 20 which is adapted to receive a portion of a nut to be cracked.

The lug 16 as shown more particularly in Fig. 40 4 is provided with a slot 21. This slot has an under-cut portion 22 at the bottom thereof to receive the lateral flanges 23 of a wedge-shaped jaw generally designated by the numeral 25. The slot 21 is of sufficient height that the wedge-shaped jaw 25 may be moved forwardly or rear-

45 wardly of the arm 14 to take care of nuts of different diameters. Naturally, for smaller nuts the wedge-shaped member 25 will be moved towards the member 10. For large nuts the wedge-shaped member will be adjusted towards the free end of the arm 14.

It will be noted from Fig. 1 that the under-cut portion of the slot 21 extends through the portion 55 26 of the arm 14 so that the lateral flanges 22 when engaged by the under-cut portions in the

handle 14 will hold the jaw in place and said jaw 25 will not fall out of the handle.

A pin 30 extends laterally from the larger end of the jaw 25; and this pin may be grasped when the jaw is moved back or forth to its adjusted position.

The lug 16 has a curved end wall 31 as shown in Fig. 1 which will partially act as a guide or stop for maintaining the nuts 32 between the jaw 20 and the jaw 25.

The operation of my device is as follows:

The inner free ends of the lugs 15 and 16 are normally spaced apart a pre-determined distance and maintained in this position by the spring members 12 as shown in Fig. 1 and a nut is placed between the jaws 20 and 25. The movable jaw 25 is adjusted to a position so that its upper face will neatly engage the bottom portion of the nut 32 while the upper portion of the nut is received by the curved jaw 20.

Pressure on the arms 13 and 14 towards each other will cause the shell of the nut to crack without breaking the meat of the nut. The free ends of the lugs will come in contact with each other as the shell is completely broken; and these lugs therefore act as stops to further limit inward movement of the jaws 20 and 25. It will be seen by this construction that a nut cracker is provided which will break the shell of the nut without injuring the meat of the nut, because the crushing movement of the arms 13 and 14 is limited by the lugs 15 and 16 while the movable jaw 25 when properly adjusted will maintain the nut 32 in snug engagement with the jaws 20 and 25.

I claim:

1. A nut cracker comprising a pair of arms connected at one of their ends for relative movement, stops on each arm cooperating to limit their closing movement, one of the arms having a

recess adjacent the stop thereon and forming a nut receiving jaw, the other arm having an opposing longitudinal guideway extending through its stop and a wedge block movable in said guideway and forming in combination with said stop a second nut jaw.

2. A nut cracker comprising resiliently connected arms, a nut jaw formed on the inner side of one of the arms, the other arm having on its inner face a guideway undercut at its lateral edges and extending at each side of the area of the aforementioned jaw, a wedge shaped member slidably mounted in the guideway and forming a second nut jaw cooperating with the first mentioned jaw to accommodate nuts of various diameters, and lugs on the respective arms for limiting the closing movement of the arms positioned between the inner edges of said jaws and the connected ends of the arms and forming portions of each of said jaws.

WILLIAM M. GALLAGHER.
